UNITED STATES PATENT OFFICE

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY

HEEL-ATTACHING MACHINE

Application filed August 4, 1926, Serial No. 127,034, and in Great Britain April 24, 1926.

This invention relates to machines for use in attaching heels to shoes and is herein illustrated as embodied in a machine of a type particularly adapted for carrying out the 5 method of wood heel attaching disclosed in United States Letters Patent No. 1,615,258, granted Jan. 25, 1927, upon an application filed in the name of Maurice V. Bresnahan, although in various aspects the invention is 10 not limited to embodiment in a machine of that type nor to use in practising that method.

A machine capable of use in practising the above-mentioned method is disclosed in my co-pending application Serial No. 54,046, 15 filed Sept. 2, 1925, of which the present application is a continuation in part. The machine just referred to comprises a clamping device for holding a wood heel in assembled relation with a shoe mounted on a last, while 20 a hole is being bored in the heel through a fastener-receiving hole in the last and while a fastener is being inserted through the hole in the last into the hole in the heel to secure the heel to the shoe during the setting 25 of an adhesive which has been applied between the heel and the shoe.

The present invention has for one object the provision of an improved supporting device arranged to maintain a last, upon which 30 the shoe is mounted, in an upright position with the fastener-receiving hole in the last extending in a vertical direction and with the heel in assembled relation with the shoe. This object has been attained by the provision 35 of a novel shoe supporting device comprising the combination with a pivotally mounted table or tread plate for supporting the rear of a shoe by engagement with the tread face of the heel thereof, of a toe plate 40 yieldingly mounted upon said table for supporting the forepart of the shoe. The pivotal mounting of the table permits a shoe supported thereby to be tilted to bring the fastener-receiving hole in the last into a vertical 45 position, whereas the yielding mounting of the toe plate permits the latter to yield if necessary to enable the tread face of the heel of the supported shoe to lie flat upon the pivoted table irrespective of differences in the 50 angular relations of the planes of the tread

faces of the heel and the sole. Furthermore, since the toe plate is carried by the pivotally mounted table, any advantage obtained from the yielding mounting of the toe plate will remain irrespective of the position of tilting 55 adjustment of the tread plate.

Another object of the invention is to provide a clamping device of the character described with means for quickly and conveniently adjusting its members to accommodate 60 shoes of different sizes and heels of different heights. To the accomplishment of this object a further feature of the invention consists in the provision of a clamping member for engaging the cone of a last upon which 65 a shoe is mounted, a support opposite the last engaging member arranged to engage the tread surfaces of the heel and sole of the shoe and to co-operate with said member to clamp 70 the heel to the shoe, and unitary means for effecting relative adjustment of said support and said last engaging member. In the embodiment of the invention shown in the drawings, the above described parts are mounted 75 above a horizontally disposed portion of a frame work which serves as a tray or bench and the means for effecting the relative adjustment of the clamping members is located above the surface of the bench where it is readily accessible to the operator. As shown 80 the adjusting means comprises a hand wheel having screw-threaded engagement with a stem upon which one of the co-operating clamping members is mounted, rotation of the hand wheel moving said clamping member 85 toward or from the co-operating clamping member.

Another object of the invention is to locate successive lasts, upon which shoes are mounted, in a manner conducive to uniformity of 90 operation in the attachment of heels to the shoes. Since the boring and fastener inserting operations are performed at the heel ends of the shoes, the foregoing object is attained by supporting successive shoes with the heel ends of their lasts occupying the same position irrespective of variations in the style of lasts and height of heels being operated upon. Accordingly a further feature of the invention 95 consists in the provision of means for 100

engaging and supporting a lasted shoe having a heel in assembled relation therewith, and a clamp member for applying pressure to the cone of the last, movable into a predetermined position to act as a gage in adjusting said shoe engaging means to support successive shoes with the cones of their lasts occupying the same position notwithstanding variations in the style of the lasts or the height of the heels.

10 In order to prevent the pivotally mounted shoe supporting table from being tilted by the action of the last engaging clamping member in applying the clamping pressure, the invention provides for mounting the 15 clamping member for movement from an idle position into a last engaging position and subsequently substantially in a direction toward the axis of pivot of the table to apply 20 clamping pressure to the top of a last upon which the supported shoe is mounted.

The various features of the invention will be best understood from a description of the preferred embodiment thereof, illustrated in the accompanying drawings, in which—

25 Fig. 1 is a view in side elevation of a heel attaching machine with parts broken away, showing particularly the construction of the clamping device;

30 Fig. 2 is an enlarged view in side elevation of the clamping device;

35 Fig. 3 is a detail view in perspective of the shoe supporting table, parts being broken away to show the manner in which the table is adjusted; and

40 Fig. 4 is a rear view of the mechanism shown in Fig. 2.

Referring to the drawings, the illustrated device is adapted to operate upon a shoe S (Fig. 1) having a heel H in assembled relation therewith, the shoe being mounted upon a last L provided with a fastener-receiving hole X which extends from the top of the cone to the bottom of the heel seat portion of the last. The device comprises a base 45 framework 10 supporting a tray or bench 12, a shoe supporting table 14, which is located above the bench or tray, and a last engaging clamping member 70 which is arranged to cooperate with the table 14 to clamp the shoe 50 and the heel and the last together.

The shoe supporting table 14 (Fig. 3) is 55 pivotally connected at 16 to a base 38 and comprises a heel plate 18 for engaging and supporting a heel such as the heel H of a shoe S, and a vertically-adjustable toe plate 20 for engaging and supporting the forepart of the shoe. As shown in Fig. 2, the lower side of the plate 20 is provided with a stem 22 which fits into a hollow projection 24 formed on the forward extremity of the shoe supporting table 14. A plug 26 fills the lower opening in the hollow projection 24 and provides a fixed abutment upon which one extremity of a compression spring 28 rests.

The other extremity of the spring 28 bears against the end of the stem 22 and tends normally to urge upwardly the toe plate 20, while a slot and bolt arrangement 30 limits the extent of vertical movement which may be imparted to the toe plate. As before mentioned, the table 14 is pivoted at 16 for vertical tilting movement, and a compression spring 32 located beneath the table tends normally to tilt the forepart of the table upwardly. The 70 extent of this upward tilting movement is limited by means of a stop here illustrated in the form of a screw 36, which engages the rear of the table, as best shown in Figs. 1 and 4.

An advantage of mounting the shoe supporting table 14 for tilting adjustment in the manner described is that the stop 36 may be adjusted to cause raising or lowering of the forepart of the table against the action of the compression spring 32, thereby permitting a supported shoe to be tilted to position it so that the hole X in its last will be vertically disposed. By thus positioning the shoe, the tool which bores the hole in the heel and the tool which inserts the fastener (each of said tools being power driven and constituting a part of the complete heel attaching machine) may be more simply constructed and arranged than would be required for operating not only in a vertical direction but also in directions at an angle to the vertical.

Also, if desired, the table may be tilted to facilitate seating of the heel upon the heel seat of the shoe. For example, if the rim of the heel does not snugly engage the heel seat of the shoe at the breast line, the forepart of the table 14 may be tilted upwardly to force the heel closely against the shoe at this point. Similarly, if the rear of the heel does not snugly engage the heel seat of the shoe, the forward part of the table 14 may be tilted downwardly to raise the rear of the heel and thereby close any gap which may exist between the heel and the shoe and secure a close joint in this locality.

The spring beneath the toe plate 20 permits the latter to yield if necessary to enable the tread face of the heel to lie flat upon the tread plate 18 of the table irrespective of differences between the planes of the forepart of the sole and the tread face of the heel.

A back rest 46, cupped out to receive the rear of the heel of the supported shoe, is mounted for adjustment longitudinally of the table 14 for the purpose of locating successive shoes with their heel ends in the same position relatively to the stationary parts of the machine. Since the boring and fastener inserting operations are performed upon the heel ends of the lasts, it will be appreciated that the provision of means to locate the heel ends of successive lasts in the same position will afford uniformity of operation, in boring and attaching successive heels, that could not 120 125 130

otherwise be attained. To the end of permitting horizontal adjustment of the rest 46, the base 38 is provided with a groove 40 for receiving a hollow arm 42 surrounding a stem 44 upon which the back rest 46 is mounted. A screw 48 (Fig. 3) controls vertical adjustment of the rest 46 to accommodate heels of different heights.

In addition to being provided with means to position similarly the heel ends of successive lasts, the table 14 is mounted for vertical adjustment for the purpose of locating the top surface of successive lasts in the same vertical plane. Accordingly, the base 38 is provided with a screw threaded stem 50 (Fig. 3) having a groove 52 extending throughout its length. A smoothly bored sleeve 54 loosely surrounds the screw threaded stem 50 and is adapted to be inserted within a hollow boss 56 formed on the lower side of the tray 12 (Fig. 2). A set screw 58 extends through the hollow boss and has frictional engagement with the surface of the sleeve 54 to prevent relative movement between the sleeve and the boss. A second hollow sleeve 60 (Fig. 3) surrounds the inner sleeve 54 and is of shorter length than the sleeve 54 so that its lower end may rest upon the top surface of the tray 12, thereby providing an additional supporting element for the table 14. Thus it will be seen that the inner and outer sleeves 54 and 60 are rigidly mounted upon the tray 12 and that the stem 50 carrying the table 14 may be moved freely through the bore of the inner sleeve 54 to effect vertical adjustment of the table. A set screw 66 extends through the sleeves 54 and 60 preventing relative movement between them and the end of the screw 66 has frictional engagement with the bottom of the groove 52. By means of the screw 66 the table 14 may be locked in a desired vertical adjustment and rotation of the stem 50 within the sleeve 54 is prevented.

The structure defined in the preceding paragraph provides a way in which the table 14 may be manually adjusted to various heights. In addition to the provision of means for manually adjusting the table, a hand wheel 68 has been provided for effecting mechanically this adjustment. The hand wheel 68 is screw threaded upon the stem 50 and rotation of the wheel causes the table 14 to be raised or lowered as desired. It will be appreciated, inasmuch as the hand wheel 68 is located above the surface of the tray 12, that it provides a simple and easily accessible means for effecting simultaneously, vertical adjustment of the tread plate 18, the toe plate 20 and the heel rest 46.

Located above the surface of the table 14 is a clamping member 70 (Figs. 2 and 4) which is mounted for movement toward and away from the table 14 to clamp against the table the lasted shoe S and the heel H in assembled

relation therewith. The member 70 is adapted to engage and apply this clamping pressure to the cone of the last upon which the shoe is mounted and for this purpose the clamping member 70 is provided centrally of its length with a serrated projection (Fig. 4). A pair of C-shaped links 72, 74 are offset towards the forward part of the table 14 to allow the greatest amount of space to be available in positioning the shoe within the clamp, and these links carry the clamping member 70 at their upper extremities.

Intermediate between their ends the links 72, 74 are pivotally secured at 76 to the arms 75 of a U-shaped bracket mounted in the hollow bearing member 62. At their lower ends the links 72, 74 are secured to the arms 80 (Fig. 1) of a yoke 82 which is pivotally mounted on a spindle 84 carried by a bracket 86 attached to the lower extremity of the inner sleeve 54. It will be observed that arms 80 are substantially longer than the arms 75. By this arrangement, whenever the clamping member 70 is moved upwardly, links 72, 74 are pushed upwardly by arms 80 and are also rocked about the connections 76 with arms 75, to carry the clamping member 70 forwardly towards the toe end of the shoe to an inoperative position in which the clamping member will not interfere with the actions of the operative when he is engaged in placing a shoe within the clamp or removing one therefrom. By a comparison of Figs. 2 and 4, it will be observed that arms 75 are bowed upwardly and away from links 72, 74 to permit a greater forward motion of links 72, 74 than would otherwise be possible without bringing the links into engagement with these arms. The upward and forward, or inoperative, position of the clamping member 70 is adjustably determined by a threaded stop 88 which engages an abutment 90 formed on the bracket 86.

Arms 72, 74 are rocked to operate the above described clamping apparatus by means of yielding adjustable connections from a suitable treadle 92 (Fig. 1). The treadle 92 is connected to a two-part treadle rod 94 which may be adjusted for length by means of a turn buckle 96. A coil spring 98 extends between the projection 86 and an arm 100 on the rod 94 and is for the purpose of holding the treadle and the movable parts of the clamping apparatus in their upper or idle position. The upper extremity of the treadle rod 94 is formed into a head 102 against which one end of a spring 104 bears, the lower end of the said spring being arranged to bear against a yoke 106 connected to the arms 80. Since the rod 94 is free to move through the lower extremity of the yoke 106, it will be understood that the arrangement just described provides a yielding connection between the rod 94 and the arms 80 to which the yoke 106 is connected. A nut 108 screwed upon the rod 94 pro-

vides means for adjusting the compression of spring 104 and also serves as means to transmit to the yoke 106 any upward movement imparted to rod 94.

5 While it is usually preferred to hold the clamp by standing on treadle 92, yet, if desired, as an alternative construction, a shoe may be held under clamping pressure, by means of a pawl 110 (Fig. 1) engaging a 10 ratchet 112 carried by a brace 114. The pawl 110 is herein illustrated in the form of an auxiliary treadle 116 pivotally mounted at 111 upon the treadle 92 and is held against ratchet 112 by means of a spring 118. Thus depression 15 of the treadle 92 causes the clamping member 70 to be locked in its downward position by reason of pawl 110 engaging ratchet 112 and depression of the treadle 116 causes the pawl 110 to move out of engagement with the ratchet 112 to release the treadle 92 and permit upward movement of the clamping member 70.

The device is provided with a latch or gage 120 for use in setting up the clamping device 25 whenever a change occurs in the style of the last or height of the heel being operated upon. The latch 120, which is shown in its inoperative position in Fig. 1, is movable into the position shown in Fig. 4 to straddle 30 the inner projecting end of the spindle 76 upon which the arm 72 is pivotally mounted. When the spindle 76 is so straddled by the gage 120, the clamping member 70 occupies an operative gaging position, preliminary 35 to applying pressure; the member 70 has moved from the dotted line position of Fig. 2, across the top of the arc through which it is constrained to move, and occupies the full line position shown in Fig. 2. Further movement of the member 70, from its gaging position, takes place substantially along the line A—B (Fig. 2) and substantially in the direction of the axis of pivot 16 of the table 14. As already pointed out, the latch 120 40 is arranged to hold the member 70 in its gaging position. When so held, the operator of the machine places the shoe, for which he is setting the clamping device, beneath the bar 70, with the serrated projection formed on 45 the bar engaging the cone forward of the perforation passing through the last, and in a position to avoid interference with the jack-pin hole. Next the hand wheel 68 is rotated to cause elevation of the table 14 until both 50 the tread surface of the heel and the sole of the shoe are engaged and supported. When 55 this has been done, the shoe is held against vertical displacement and the vertical position of the table relatively to the bar 70 is 60 determined. The horizontal position of the rest 46 is then determined by moving the rest into engagement with the rear of the heel H. When 65 the vertical and horizontal adjustments have both been made, the latch 120 is moved back into its idle position and the clamping

device is then ready to operate in the same manner upon any number of shoes of the same style and height of heel for which the device has been adjusted.

In this connection it will be appreciated 76 that in the ordinary course of shoe making a number of shoes of the same style and having the same height of heel will come to the heel attaching machine in succession, so that the clamping device, if properly adjusted for the 75 first shoe in the series, will, without requiring any additional adjustments, operate in the same manner upon all of the shoes in that series.

Having described my invention, what I 80 claim as new and desire to secure by Letters Patent of the United States is:

1. In a shoe supporting device, the combination with a pivoted tread plate for engaging and supporting the tread face of the 85 heel of a shoe, of a toe plate yieldingly mounted upon said tread plate for engaging and supporting the tread face of the sole at the forepart of the shoe.

2. In a shoe supporting device, the combination with a pivotally mounted table for supporting the rear of a shoe, and a yieldingly mounted toe plate for supporting the forepart of the shoe, of unitary means for raising or lowering the toe plate and the table. 95

3. In a device for clamping a heel to a shoe, the combination with a table for engaging and supporting the heel end of the shoe, and a yieldingly mounted toe plate for engaging and supporting the forepart of the shoe, 100 of means for effecting uniform and simultaneous vertical adjustment of the table and the toe plate.

4. In a shoe supporting device, the combination with a yieldingly mounted member 105 for supporting the forepart of the shoe and a pivotally mounted member for supporting the rear of the shoe, of means to engage and apply pressure to the top of a last upon which the shoe is mounted to clamp the last and the shoe and the heel between the last 110 engaging member and the supporting members.

5. In a device for clamping a heel to a shoe, a clamping member for engaging the cone of a last upon which the shoe is mounted, a support located opposite the last engaging member and arranged for engaging the tread surfaces of the heel and the sole of the shoe, and unitary means for effecting adjustment of said heel and sole engaging support relatively to the last engaging member. 115

6. In a machine of the class described, means for supporting a shoe by engagement with the tread faces of the heel and the sole 125 of the shoe, a member for clamping the shoe to the tread engaging means and a horizontally and vertically adjustable member for engaging the rear of the heel of a supported shoe. 120

7. In a machine of the class described, a frame, a table for supporting a shoe by engagement with the tread face of the heel of the shoe, a pivotal connection between the table and the frame arranged to permit vertical tilting adjustment of the table, a yieldable support mounted upon the forward end of said table for engaging and supporting the forepart of the shoe, and means to apply pressure to a last upon which the shoe is mounted to clamp the heel and the shoe in assembled relation against said table and the forepart support respectively. 10
8. In a machine of the class described, a pivotally mounted table for supporting a lasted shoe and a heel in assembled relation therewith by engagement with the tread faces of the heel and sole of the shoe, yielding means normally tending to hold the table in a substantially horizontal position, and a clamp member for engaging the top of the last to clamp the last and the shoe and heel in assembled relation between the last engaging member and the table. 20
9. In a machine of the class described, a table for supporting a shoe and heel in assembled relation, a member for engaging the top of a last upon which the shoe is mounted, and means for operating said member to clamp the last and the shoe and the heel between the last engaging member and the supporting table, said means comprising a foot treadle and links for supporting the clamp member connected with the treadle and arranged at opposite sides of the shoe, said links being offset toward the forepart of the shoe. 30
10. In a shoe supporting device, the combination with a member for engaging and supporting the heel of a shoe, a member for engaging and supporting the toe of the shoe, a member for engaging the rear wall of the heel of the shoe and a member for engaging the top surface of a last upon which the shoe is mounted, of unitary means for adjusting simultaneously said toe and heel engaging members relatively to the last engaging member. 40
11. In a device for clamping a heel to a lasted shoe, a member for engaging the cone of the last movable from an inoperative position to an operative position, a gage for predetermined said operative position, a support for the shoe located beneath the cone engaging member, and means for effecting adjustment of said shoe support relatively to the cone engaging member to accommodate shoes of different shapes and heels of different heights. 50
12. In a device for clamping a heel to a lasted shoe, means for engaging and supporting the lasted shoe and heel in assembled relation, and a clamp member movable into a predetermined position to act as a gage in adjusting the shoe engaging means to sup- 60
- port successive shoes with the cones of their lasts occupying the same position notwithstanding variations in the style of lasts and height of heels being operated upon. 70
13. In a device of the character described, means for engaging and supporting a lasted shoe and heel in assembled relation, a clamp member movable into a predetermined position to act as a gage in adjusting the shoe engaging means to support successive shoes with the cones of their lasts occupying the same position notwithstanding variations in the style of lasts and height of heels being operated upon and a latch for co-operating with the clamp member in predetermined the position of the latter. 75
14. In a device for clamping a heel to a shoe, a pivotally mounted table for supporting the shoe and the heel in an upright position, and means for engaging the cone of a last upon which the shoe is mounted to clamp the last and the shoe and the heel in assembled relation between the cone engaging member and the supporting table, said supporting table being adjustable to bring the cones of successive lasts upon which shoes are assembled into the same elevated position relatively to the cone engaging means notwithstanding variations in the style of lasts and height of heels being operated upon. 80
15. In a device for clamping a heel to a shoe, a pivotally mounted table for supporting the shoe and heel in an upright position, means for engaging the cone of a last upon which the supported shoe is mounted to clamp the last and the shoe and the heel in assembled relation between the cone engaging member and the supporting table, and means for engaging the rear of the heel of a supported shoe adjustable to bring the heel ends of successive lasts into the same position relatively to the cone engaging means, notwithstanding variations in the style of lasts and height of heels being operated upon. 90
16. In a device for clamping a heel to a shoe, a pivotally mounted table for supporting the shoe and the heel in an upright position, and means for engaging the cone of a last upon which the shoe is mounted to clamp the last and the shoe and the heel in assembled relation between the cone engaging member and the supporting table, said supporting table being adjustable to position the tops of the cones of successive lasts having shoes mounted thereon at the same elevation and being provided with adjustable means for similarly positioning the rear of the cones of the successive lasts, notwithstanding variations in the style of the lasts or the height of the heels. 100
17. In a device for clamping a heel to a shoe, a member for engaging a last upon which the shoe is mounted arranged for movement between an idle and a last-engaging position, means for predetermined the 105
18. In a device for clamping a heel to a shoe, a member for engaging a last upon which the shoe is mounted arranged for movement between an idle and a last-engaging position, means for predetermined the 110
19. In a device for clamping a heel to a shoe, a member for engaging a last upon which the shoe is mounted arranged for movement between an idle and a last-engaging position, means for predetermined the 115
20. In a device for clamping a heel to a shoe, a member for engaging a last upon which the shoe is mounted arranged for movement between an idle and a last-engaging position, means for predetermined the 120
21. In a device for clamping a heel to a shoe, a member for engaging a last upon which the shoe is mounted arranged for movement between an idle and a last-engaging position, means for predetermined the 125
22. In a device for clamping a heel to a shoe, a member for engaging a last upon which the shoe is mounted arranged for movement between an idle and a last-engaging position, means for predetermined the 130

last engaging position, and shoe supporting means located opposite the last engaging member, said shoe supporting means being adjustable vertically and horizontally for the purpose of positioning a supported shoe relatively to the last engaging member when the latter is occupying its predetermined last engaging position.

18. In a device for clamping a heel to a shoe, the combination with a pivoted table for engaging and supporting the heel end of the shoe, and a yieldingly mounted toe plate for engaging and supporting the fore-part of the shoe, of a clamping member adapted to move from an inoperative position to a predetermined operative position above the table and from that position substantially in a direction toward the axis of pivot of the table to apply clamping pressure to the top of a last upon which the supported shoe is mounted.

In testimony whereof I have signed my name to this specification.

FREDERIC E. BERTRAND.
